UNITED STATES PATENT OFFICE.

EDWIN H. BENNETT, JR., OF BAYONNE, NEW JERSEY.

COMBINED ELECTRIC FAN AND ELECTROLIER.

SPECIFICATION forming part of Letters Patent No. 585,250, dated June 29, 1897.

Application filed June 14, 1893. Serial No. 477,612. (No model.)

To all whom it may concern:

Be it known that I, EDWIN H. BENNETT, Jr., a citizen of the United States, residing at Bayonne, in the county of Hudson and State of New Jersey, have invented a certain new and useful Combined Electric Fan and Electrolier, of which the following is a specification, reference being had therein to the accompanying drawings.

10 My invention has for its object to provide a combined electric fan and electrolier, the latter being supported from some stationary part of the electric fan. To this end I attach to a suitable part of the fan or an adjunct thereof a support which sustains any desired number of incandescent lamps. This support or lamp-holder is preferably arranged below the wings or blades of the fan, so that the latter will not interfere with the light of 15 the lamps, the said lamp-holder being also preferably of such construction that it may readily be attached to or removed from the fan, and the electrical connections of the lamps are preferably such that they are connected with the said lamp-holder so as to be attached to or removed from the fan with said holder, said lamps being, by proper conducting-wires, in electrical connection with a contact device carried by said lamp-holder and 20 the lower part of the fan being provided with a contact device to be engaged by the contact on the lamp-holder, so that as the lamp-holder is secured in place proper circuits to and from the lamps may be established by proper contacts on the lamp-holder and fan, and the lamp-holder and its lamps may be removed without disarranging the conductors or circuits within the lamp-holder. The lamps of 25 the electrolier may, however, be arranged above the fan if so placed that a part or all of them will be outside of the fan-blades or if they be employed with a rapidly-running or disk fan.

In the accompanying drawings, Figure 1 is 30 a sectional elevation of my improved electric fan and electrolier, and Fig. 2 is a section on a larger scale than Fig. 1 to more clearly illustrate the construction by which the lamp-holder or support is attached to the fan and by which suitable electrical connections between the latter and the lamps are established. Fig. 3 illustrates a modified form of

my invention. Fig. 4 is a sectional view of the fan-motor and the electrolier.

A denotes a portion of the rod or tube which in practice may be suspended from a ceiling or other elevated point of attachment. To the lower end of the said rod or tube is secured a suitable support or bracket B, to which is attached the field-magnet C of an electric fan.

D is a rotating armature journaled on a tube b', attached at its upper end to the bracket B, said armature carrying the fan wings or blades E.

B' is an oil-cup, into which the lower end of the journal of the armature D extends, said oil-cup being screwed onto the tube b' and having outwardly-extending arms which support the brushes b of the fan-motor, and to the depending lower part of said oil-cup is screwed a metal sleeve F, held in a fixed position by a set-screw f or other suitable securing device. The exterior of the sleeve F is provided with lugs f', to which are attached, by rivets f'', a disk or plate G of vulcanized fiber or other insulating material.

F' is a second sleeve attached by rivets f''' to the insulating plate or disk G, said rivets passing through peripheral lugs f'' on said sleeve.

The sleeves F and F' are both alike, or essentially so, and each is preferably provided with three peripheral lugs, by which and the rivets f'', f''' it is connected with the plate or disk G, so that the latter and the said sleeves are all rigidly connected together, but with the two sleeves insulated from each other, these connecting parts being rigidly attached to the bottom of the oil-cup B'.

H is a sleeve exteriorly screw-threaded to fit the threaded interior of the sleeve F', into which it is screwed, the said sleeve H having peripheral lugs h for the attachment to said sleeve of the insulating plate or disk I by means of rivets h'.

J is a bracket attached by means of screws j to the insulating plate or disk I, the said bracket having a series of upwardly-extending arms j'.

K is a casing or basket, preferably formed of sheet metal and serving as a holder or support for the incandescent lamps M. K' is also a sheet-metal casing or basket, provided at

its upper part with an annular ledge *k*, on which the lower end of the casing or basket *K* rests. This smaller casing *K'* has an opening in its bottom, so that it may be placed in 5 position, as shown, over the screw-threaded sleeve *j'*, formed at the bottom of the bracket *J*, and thus when the lowermost lamp *M'* is screwed onto the said threaded sleeve the socket of said lamp will serve as a nut to secure 10 the casing *K'* in place, or the said casings *K* and *K'* may be attached together and to the arms *j* by solder or otherwise.

The conductors *a* and *a'* to carry the electric current to and from the lamps are preferably 15 passed down through the tube *b'*, one of said conductors being attached to the contact-block *N*, which is fixed to the insulating plate or disk *G*, while the other of said conductors is attached to one of the rivets *f*³ which secure 20 the sleeve *F* to the said insulating-disk *G*. The current entering by the conductor *a* can thus pass through said rivet *f*³ to the sleeve *F'*, and from the latter to the sleeve *H*, and from said sleeve through the conductors 25 *m* to the lamps.

Attached to the insulating plate or disk *I* is a metal contact-block *O*, which when the sleeve *H* is screwed into the sleeve *F'* comes against the metallic contact-block *N*, rigid 30 with the sleeves *F* and *F'*. Thus the current passing from the lamps through the conductors *n* and the contact-block *O* passes to the contact-block *N* and thence outward through the conductor *a'*. The conductors *m* extend 35 from the sleeve *H* to the lamps, while the conductors *n* extend from the lamps to the contact-block *O*.

It will thus be seen that the lamp-holder, consisting of the sleeve *H*, the bracket *J*, and 40 the casings *K* and *K'*, may, with all of their electrical connections, including the conductors *m* and *n*, be attached to or detached from the depending part of the oil-cup *B'* merely by screwing the sleeve *H* into the sleeve *F'*.

By attaching this electrolier or incandescent-lamp holder to an electric fan, below the fan wings or blades of the latter, I am enabled to provide an electrolier and electric fan of such construction that the fan-blades 50 will not interfere with the light from the lamps.

It will also be apparent that the electrolier forms an ornamental finish for the fan and incloses the rougher parts of the fan-motor, 55 while at the same time the construction of the parts is such that the electrolier may be readily secured in place or easily removed from the fan when desired. I do not, however, wish to be understood as limiting my 60 invention to an arrangement of the lamps below the fan-blades, as they may be placed above the same, as shown in Fig. 3, if so arranged as to be partly or wholly outside of

the fan-blades, so that the latter will not interfere with the light, or if they be employed 65 with a rapidly-running or disk fan, which would interfere but little with the light.

Having thus described my invention, I claim, and desire to secure by Letters Patent— 70

1. The combination with an electric fan, and a central support for said fan and its motor, of an electrolier also sustained by said central support and comprising a plurality or series of electric lamps which are carried 75 by a holder detachably connected with said central support so that the lamps carried thereby may be removed from the fan, collectively, by detaching said holder.

2. The combination with an electric fan, the oil-cup or lower part of which is provided with a suitable contact, of an electrolier or lamp-holder removably connected with said part or oil-cup and provided with a contact to engage the first-named contact when said lamp-holder is secured in place, and suitable electric conductors between the holder-contact and the lamps; whereby said lamp-holder may be removed from the fan without disturbing said conductors. 80

3. The combination with an insulated sleeve, as *F'*, connected with the lower portion of a part of an electric fan, of a second sleeve, as *H*, in direct electrical connection with the said insulated sleeve, a lamp-supporting bracket insulatingly attached to the said second sleeve, and a lamp-holder carrying a series of incandescent lamps and sustained in place by the said lamp-supporting bracket. 90

4. The combination with the oil-cup *B'* of an electric fan, of the sleeve *F* attached to the lower portion of the said oil-cup, an insulating plate or disk *G* attached to the said sleeve *F*, a second sleeve *F'* attached to the 105 said insulating plate or disk, the sleeve *H* secured to the said sleeve *F'*, the insulating plate or disk *I* attached to said sleeve *H*, the fan-supporting bracket *J* attached to the said insulating plate or disk *I*, the contact-blocks 110 carried by the said plates or disks *G* and *I*, conductors to and from the lamps and one of the said contact-blocks and the sleeve *H*, to form circuits within the lamp-holder.

5. The combination with a central shaft, of 115 an electric motor supported thereby and having a portion which is revoluble thereon and which carries fan-blades, and an electrolier rigidly supported by said shaft and comprising a plurality or series of electric lamps. 120

In testimony whereof I affix my signature in presence of two witnesses.

EDWIN H. BENNETT, JR.
